United States Patent Office.

GARRETTSON SMITH AND HENRY BROWN OF PHILADELPHIA, ASSIGNEES TO E. S. SHANTZ AND JOSEPH JOHNSON, OF ROYAR'S FORD, PENNSYLVANIA.

Design No. 3,487, dated May 11, 1869.

DESIGN FOR A STOVE.

The Schedule referred to in these Letters Patent and making part of the same.

To all whom it may concern:

Be it known that we, GARRETTSON SMITH and HENRY BROWN, of the city of Philadelphia, in the State of Pennsylvania, have invented or produced a new and original Design for a Stove, which we have named "Morning Light;" and we do hereby declare that the following is a full and exact description of the same, reference being had to the accompanying drawings, making a part of this specification, in which—

Figure 1 is a perspective view of the whole stove, and

Figure 2, a like view of the middle portion of the same, detached and enlarged.

Like letters of reference indicate the same parts when in both figures.

The stove may be divided, for consideration, into

four distinctive parts, viz, the base A B, the body C D, the middle E F, and the upper portion G H, together with the encircling mouldings a' , b' , c' , f' , and h' thereof.

The design consists in the profile or contour produced by the assemblage of the said parts together, producing a whole as represented in fig. 1.

What we claim as our invention, and desire to secure by Letters Patent, is—

The design for a stove herein set forth.

GARRETTSON SMITH.
HENRY BROWN.
